UNITED STATES PATENT OFFICE.

WILLIAM S. GOODELL, OF CHICAGO, ILLINOIS.

INTERCHANGEABLE ROAD-TREATING MACHINE.

Application filed March 1, 1922. Serial No. 540,091.

To all whom it may concern:

Be it known that I, WILLIAM S. GOODELL, a citizen of the United States, residing at Chicago, in the county of Cook and State of Illinois, have invented a certain new and useful Improvement in Interchangeable Road-Treating Machines, of which the following is a full, clear, concise, and exact description, reference being had to the accompanying drawings, forming a part of this specification.

This invention relates to improvements in interchangeable road-treating machine.

One object of the invention is to provide an entirely practical, efficient and relatively inexpensive machine especially adapted for the treating of soft clay and gravel roads.

Another object of the invention is to provide a machine of the character indicated interchangeably adapted for scarifying, scraping, rolling and surfacing roads.

A specific object of the invention is to provide a machine of the character indicated employing a weighted roller, the position of which is shiftable or adjustable for the purpose of either varying the effective load or weight of the machine when it is performing certain functions or to act as a true leveling or smoothing roller.

Other objects of the invention will more clearly appear from the description and claims hereinafter following.

In the drawings forming a part of this specification, Figure 1 is a top plan view of a machine showing my improvements in connection therewith, certain parts being shown in section in order to more clearly illustrate details of construction. Figure 2 is a side elevation of the machine shown in Figure 1 and illustrating the arrangement of parts when the machine is adapted for either scarifying or scraping. In this figure the adjustable weighted roller is shown in full lines in a position trailing the rear wheels of the machine approximately at the road level. The dotted views of said roller indicate other positions which said roller may assume for the purposes herein-after set forth. Figure 3 is a view similar to Figure 2 but illustrating the machine when employed for smoothing or rolling the road bed. Figure 4 is a detail sectional view corresponding substantially to the line 4-4 of Figure 2 to more clearly illustrate one of the scarifying prongs and method of securing the same in adjusted position.

And Figure 5 is a detail sectional view corresponding substantially to the line 5-5 of Figure 1 illustrating more particularly the method of holding the rear weighted roller in adjusted position.

In said drawings, the machine is shown as comprising a frame designated generally by the reference character A; a front rolling support B; rear wheels C-C; a weighted rear roller D; a scarifier E; a scraper F; a gravel or other surfacing material hopper G; and a liquid surfacing material tank H.

The frame A may be of any suitable substantial construction, the one shown in the drawings being formed of a plurality of channels 10-10 arranged in a rectangular form and suitably united at the corners by gussets 11-11. Suitable cross braces and platform supports may be employed as indicated at 12-12 in Figure 1.

The rolling support provided for the machine at the front end thereof is preferably in the form of a wide tread roller indicated at B, the same being weighted and of a width corresponding substantially to the width of road bed to be treated. In actual practice, the roller B will preferably consist of an outside shell or tubular casing 13 and a concrete filling 14 with suitable anchors 15 for the concrete, the anchors 15 being rigidly carried by the axle 16 which is extended thru the roller and suitably journaled, preferably in roller bearings, carried by the depending arms 17-17 secured to the frame.

The rear wheels C are arranged as indicated, one on each side of the machine outside of the frame, the same being preferably rotatably mounted on a fixed axle 18, ball bearings being also preferably employed. In this connection it will be noted that the rims of the wheels C are concave in cross section, as indicated at 19 to thereby minimize tendency of the machine to sideslip when on a crowned road bed or when the scraper is being employed, which also has a tendency to shift the machine sideways.

The machine is adapted to be pulled, preferably by one or two horses or a tractor, thru a chain 20 attached to the machine for this purpose. When horse drawn, it will be understood that the chain will have a whiffletree secured thereto, although the same is not shown in the drawing.

The scarifier E extends transversely of the machine and at right angles to the side

members of the frame. As shown, the scarifier includes an angle iron 21 pivotally attached to the frame as indicated at 22 so as to adapt it to be swung from its operative position shown in full lines in Figure 2 to its inoperative position, as shown by the full lines in Figure 3. The adjustment of the scarifier is effected by any suitable means—as for instance, the link 23 connected to 10 the hand lever 24, which is pivoted to a suitable bracket 25 carried by the frame, said lever 24 having a hand grip and located so as to be convenient to the operator when the latter is sitting in the seat 26 15 supported on the frame. Suitable locking dog and stationary rack 27 and 28 may be employed in connection with the lever 24 to hold the scarifier in any adjusted inoperative position. In operative position, the upper flange 29 of the angle iron will bear 20 against the under sides of the side members of the frame so as to prevent the scarifier from swinging counterclockwise as viewed in Figure 2. In addition to the angle iron 21, 25 the scarifier includes a plurality of vertically extending fingers, or bars indicated at 30. The latter are preferably of isosceles triangle cross section as shown in Figure 4 and the same are adapted to be held in vertically adjusted position with respect to the angle iron 21, by any suitable means such as the U-shaped clamping bolt 31, nuts 32 and filler 33 interposed between said bolt 31 and the bar proper. Each of said bars 30 is 30 oppositely beveled at its ends as indicated at 34—34 so that either end of the bar may be employed in scarifying the road bed. The bars 30 may be laterally spaced any suitable or desired distance.

40 The scraper F is of novel form and of inexpensive but substantial construction, the same as shown, consisting of a length of channel as best seen in Figure 2 with the web of the channel extending vertically when the scraper is in normal operative position. The scraper F will extend angularly with respect to the side members of the frame A and in operative position, the upper flange 35 will bear against the under 45 sides of the frame members so as to prevent the scraper from swinging counterclockwise as viewed in Figure 2. In order that the scraper may be moved to an inoperative position clear of the ground, the same is preferably pivotally supported from the frame of the machine as by brackets 36—36 mounted on studs 37—37 carried by brackets 38—38 rigidly secured to the side members of the frame A. In this connection, it will be noted that the pivotal axis of the scraper F extends parallel to the scraper as best shown in Figure 1. In order to adjust the position of the scraper, any suitable mechanism may be employed to 50 swing it in a clockwise direction as viewed

in Figure 2. Such mechanism may embody a link 39 and lever 40 similar to the lever and link arrangement for positioning the scarifier E, the lever 40 being also located so as to be convenient of operation.

70 The weighted roller D, per se, is preferably of the same type as the front roller B but of somewhat greater length and greater diameter so as to obtain greater weight. In both the rollers B and D, end plates 41 are 75 preferably employed spot-welded or otherwise permanently secured to the pipe casing or shell so as to prevent disintegration and falling away of the concrete. Said roller D is rotatably mounted in bearings 42—42 80 formed at the outer ends of a pair of brackets 43—43. The brackets 43 are in turn pivotally or circularly adjustably mounted on the stationary axle 18. In this connection, it will be noted that the brackets 85 43 are of sufficient length so as to permit the roller D to be swung around the wheels C without engaging the latter. Each of said brackets 43, at its hub end, is provided with a rigid notched wheel 44 with which is 90 adapted to cooperate a gravity influenced locking dog 45 pivotally mounted on a suitable portion of the frame, as indicated at 46. The notches 47 in the wheel 44 and the cooperating end of the dog 45 are such that, when they are in engagement, the wheel 44 and consequently the brackets 43 will be prevented from rotating in either direction. In actual practice, the weight of the roller D will preferably be between 500 and 600 100 pounds and in order to adjust it, any suitable means may be provided but preferably, for simplicity and cheapness, the brackets 43 will be made of such cross section as to 105 provide a plurality of arms 48—48 extending in different directions, said arms having openings therethru thru which to engage a rope or cable so that the horses or other tractive power may be utilized to lift the roller D to any desired position where it 110 may be locked by means of the dogs 45 and wheels 44.

115 In order to obtain the greatest use of my improved machine, I may employ the tanks or receptacles G and H. The former is located well forward of the machine and is adapted to contain gravel or other dry surfacing material. Said tank or container G will have a discharge outlet at the bottom 120 thereof extending transversely of the machine so as to permit graduated and controlled discharge of the gravel or other material on to the road. The tank or container H is more especially adapted for liquid or semi-liquids and will also have a controlled 125 discharge, as will be understood by those skilled in the art.

130 From an inspection of Figure 2, it will be noted that the effective level of the scraper F is slightly lower than that of the scarifier

E so that both scarifying and scraping may be carried on simultaneously. By adjusting the roller D to the position indicated in Figure 3, it will be noted that the weight of the rear portion of the machine is taken off of the wheels C and is sustained entirely by the roller D so that the latter is adapted to act as a true smoothing or leveling roller and with a maximum weight imposed thereon. When the machine is being used for rolling purposes, the scarifier and scraper will preferably be shifted to inoperative positions as indicated by the dotted lines in Figure 3. Not only does the mechanism described permit of the adaptation of the machine for rolling, as above described, but it also facilitates the passage of the machine over railroad tracks and the like without danger of the scarifier or scraper becoming caught or broken. As clearly indicated in Figure 2, the roller D may assume other positions than that of sustaining the weight of the rear portion of the machine and said other positions of the roller D will depend upon the effective weight desired on the machine to hold it down in carrying out its scarifying or scraping operations. In the position of the roller D shown by full lines in Figure 2, the roller D travels on the top of the road bed without imposing any substantial weight on the machine. This is desirable under some conditions, as for instance when the machine is being employed to deposit surfacing material on the road bed. By lifting the roller D to the position indicated at D' in Figure 2, a part of the weight of the roller D is imposed upon the frame but in such a position as to detract somewhat from the effective weight of the front roller B. In positions of the roller D, as indicated at D² and D³, the whole weight of the roller is carried by the frame, the position D³ producing a greater weighted effect on the forward portion of the machine, thus serving more effectively to maintain the scarifier and scraper in the dirt or gravel so as to perform their proper functions.

From the preceding description, considered in connection with the drawings, it will be seen that the machine which I have invented can be manufactured at comparatively small expense and yet will perform the functions of several machines, which are of more expensive character, as heretofore commonly employed. Because of the simple arrangement of parts, my improved machine may be readily changed or converted from one use to another.

Although I have not shown the same on the drawing, it will be understood by those skilled in the art that I may attach a gutter plow on either side of the machine, thus further increasing the utility of the machine.

Although I have herein shown and described what I now consider the preferred

manner of carrying out my invention, the same is merely illustrative and I contemplate all changes and modifications that come within the scope of the claims appended hereto.

70

I claim:

1. In a machine of the character described, the combination with a suitable frame having front and rear rotatable supporting means; of a weighted roller at the rear end of the machine, said roller being adjustably mounted on said frame and means for holding said roller in either a position below said rear supporting means of the machine to thereby sustain a portion of the machine's weight and act as a roller, or in various positions off of the road bed whereby its weight is applied to the effective holding down of the machine.

2. In a machine of the character described, the combination with a frame having front rolling supporting means and rear rolling supporting means; of a scraper supported from said frame; and a weighted roller at the rear of the machine and means for adjusting said roller either to a position where it engages the road bed below the level of the lowest portion of said rear rolling supporting means to thereby sustain a portion of the load of the machine and act as a roller, or to other more elevated positions out of contact with the road bed.

3. In a machine of the character described, the combination with a frame having front rolling supporting means and rear rolling supporting means; of a scraper supported from said frame; and a weighted roller circularly adjustable about an axis on the frame and means for holding said roller either in a position below the rear supporting means to sustain a portion of the weight of the machine or spaced from the road bed to add the weight thereof to that of the machine.

4. In a machine of the character described, the combination with a frame having front rolling supporting means and rear rolling supporting means; of a scarifier adjustably mounted on said frame; a scraper adjustably mounted on said frame; and a weighted roller also adjustably mounted on said frame and means for locking said roller either in a position below the rear supporting means, where it sustains a portion of the weight of the machine and is thereby adapted to act as a roller or in other positions spaced from the road bed to add the weight thereof to the effective weight of the machine.

5. In a machine of the character described, the combination with a frame having front rolling supporting means and rear rolling supporting means; of a scarifier mounted on said frame and adjustable from operative to inoperative position; a scraper

120

125

- mounted on said frame and adjustable from operative to inoperative position; a weighted roller at the rear of the machine circularly adjustable with respect to a fixed axis on the frame; and means for locking said roller in adjusted position, above and below the normal line of contact between the road bed and the rear supporting means.
6. In a machine of the character described, the combination with a frame having a front supporting weighted roller of a width approximating the width of the road bed to be treated by the machine, and a pair of rear wheels for supporting the rear portion of the frame; a scraper carried by said frame; and a weighted roller disposed at the rear end of the machine also approximating the width of road bed treated by the machine, and means for adjusting said rear weighted roller to either a position in contact with the road bed to sustain a portion of the weight of the machine or other positions spaced above the road bed where its weight is added to the effective weight of the entire machine.
7. In a machine of the character described, the combination with a frame; of a front supporting roller for the frame, having an extended tread approximating the width of the frame; a scarifier extending transversely of the frame in the rear of said roller; a scraper extending diagonally of the frame and located rearwardly of the scarifier; rear supporting wheels for the frame; and a rear weighted roller having a wide tread approximating the width of the frame, said rear weighted roller being circularly adjustable about a pivotal axis coinciding with the axis of said rear wheels.
8. In a machine of the character described, the combination with a frame having front rolling, supporting means, and rear rolling, supporting means; of road surface treating means depending from said frame; a weighted roller adjustably mounted on said frame, said roller being successively adjusted to positions in front of, above, to the rear of and below the axis of said rear rolling supporting means; and means for holding said weighted roller in said adjusted positions, whereby the roller is adapted to either exert a bearing pressure on said treating means or sustain a portion of the weight of the machine.

In witness that I claim the forgoing I have hereunto subscribed my name this 24th, day of February, 1922.

WILLIAM S. GOODELL.
